J. HOCKE.

MOTOR TRUCK.

APPLICATION FILED OCT. 31, 1921.

Patented Aug. 15, 1922.

FIG. 1.

FIG. 2.

FIG. 3.

Inventor:

Johann Hocke

By Lawrence Langue
Attorney

UNITED STATES PATENT OFFICE.

JOHANN HOCKE, OF WEHETITZ, NEAR KARLSBAD, CZECHO-SLOVAKIA, ASSIGNOR
TO FRITZ MEYER, OF BASEL, SWITZERLAND.

MOTOR TRUCK.

1,425,965.

Specification of Letters Patent. Patented Aug. 13, 1922.

Application filed October 31, 1921. Serial No. 511,880.

To all whom it may concern:

Be it known that I, JOHANN HOCKE, a citizen of the Republic of Czecho-Slovakia, and resident of Wehetitz, near Karlsbad, 5 Czecho-Slovakia, have invented new and useful Improvements in Motor Trucks, of which the following is a full, clear, and exact specification.

The present invention relates to a motor 10 truck with removable body, in which the bottom of the removable body rests upon the underframe of the car by means of two roof-like positioning brackets of male and female form so as to engage with one another in order to ensure or adjust the correct relative position between the underframe and the removable body of the car.

The accompanying drawing shows by way of example an embodiment of the present invention;

Figs. 1 and 2 are end views of the car, with its body shown in transverse section, lowered upon the underframe of the car and raised therefrom respectively, whilst

Fig. 3 is a plan view of a modification of the underframe.

As it is well known, the car body *a* (Figs. 1 and 2) is raisable by means of jacks *b* arranged on the underframe *c* and capable 30 of being supported upon stays *d* arranged on the car body so as to be capable of being lowered on to the earth, so that after actuating the jacks in the reverse direction, the underframe can be carried away from 35 beneath the car body which remains in place and afterwards be conveyed again below the same to allow of lowering of the car body upon the underframe.

The arrangements designed to ensure or 40 adjust a correct seating of the car body *a* on the underframe *c* consists in that the car body is provided on the lower face of its bottom with a positioning saddle *e* constituting a hollow or female bracket and arranged to fit over a corresponding male 45 roof-like positioning bracket *f* (Figs. 1 and 2) provided on the underframe. It is obvious that, owing to this female and male engagement of the positioning brackets, 50 when the underframe happens to be conveyed somewhat obliquely under the car body, the laterally displaced relative positions of the body car and the underframe can be automatically compensated on the 55 lowering of the car body, the lateral walls

of the saddle *e* sliding on those of the bracket *f* to adjust themselves to the correct middle position.

The positioning bracket *f* is grooved transversely in its forward and rearward part to receive the roof-like transverse beams *g* connected with the jacks *b*, these transverse beams, owing to their particular form, serving additionally to positioning purposes to ensure the correct seating of 65 the saddle *e* or the car body.

Instead of extending throughout the length of the car, the roof-like bracket on the underframe can be formed by several 70 separate roof-like transverse beams *h* rigidly connected to the underframe, as shown for example in the modification of Fig. 3.

Furthermore, the male positioning bracket may be provided on the underside 75 of the car body with its top or ridge turned downwards, whilst the hollow or female positioning bracket may be provided on the underframe with its hollow seats turned upwards.

What I claim is:

1. In a motor truck, an underframe, a 80 movable car body thereon, means to raise said car body from the underframe and male and female roof-like positioning brackets on the underframe and the car body to ensure or adjust correct seating of the latter upon the underframe.

2. In a motor truck, an underframe, a 85 movable car body thereon, means to raise said car body from the underframe, a female positioning bracket in form of a saddle on the underside of the car body and a male roof-like positioning bracket on the underframe to receive the said saddle bracket for adjusting or positioning purposes.

3. In a motor truck, an underframe, a 90 movable car body thereon, means to raise said car body from the underframe, a female positioning bracket in form of a saddle on the underside of the car body and a male roof-like positioning bracket on the underframe to receive the said saddle bracket for adjusting or positioning purposes, the underframe being provided with 95 raisable roof-like transverse beams arranged for the raising of the car body and to contribute also to the positioning of the latter on the underframe.

4. In a motor truck, and underframe, a 100 movable car body thereon, means to raise 105

said car body from the underframe, a female positioning bracket in form of a saddle on the underside of the car body and a male roof-like positioning bracket on the underframe to receive said saddle bracket for adjusting or positioning purposes, said male roof-like positioning bracket being formed of several separate roof-like transverse beams.

In witness whereof I have hereunto signed my name this 6th day of October 1921, in the presence of two subscribing witnesses.

JOHANN HOCKE.
